UNITED STATES PATENT OFFICE.

PATRICK B. DELANY, OF SOUTH ORANGE, NEW JERSEY, ASSIGNOR TO DELANY TELEGRAPHIC TRANSMITTER COMPANY, OF NEW YORK, N. Y., A CORPORATION OF MAINE.

TELEGRAPHY.

1,149,428.

Specification of Letters Patent. Patented Aug. 10, 1915.

Application filed January 9, 1911, Serial No. 601,571. Renewed June 2, 1915. Serial No. 31,791.

To all whom it may concern:

Be it known that I, PATRICK B. DELANY, a citizen of the United States of America, residing in South Orange, county of Essex, 5 State of New Jersey, have invented a certain new and useful Improvement in Telegraphy, of which the following is a specification.

This invention relates to a system of telegraphy in which dots and dashes, constituting component parts of signals, as in the Morse and Continental codes, are transmitted from a sending station to a distant station over a circuit composed in whole or in part of two conductors that may be indefinitely separated except at terminals. The 10 dots and dashes are distributed between these two conductors so that the signal impulses on either one of them will be unintelligible. Such a system, broadly, is disclosed in United States Letters Patent granted to me January 17, 1911 No. 981,845. The 15 present invention comprises the use of an ordinary Morse key with which all operators are familiar and the transfer of the circuit 20 from the transmitting battery to the two conductors forming the main line is effected by local devices controlled by the Morse key.

In the drawing: Figure 1 is a diagrammatic illustration showing the main line 25 composed of two conductors brought together at the transmitting and receiving stations. Fig. 2 is a diagrammatic view showing a somewhat similar arrangement except that the main line circuit is composed 30 of sections one of which is a single conductor and the others have double conductors.

Referring to Fig. 1, terminal stations are 35 marked respectively 1 and 4, and are connected by main line conductors 5, 6. At 40 each station there is a circular toothed contact plate 7 with which the line conductor 5 is connected. Between the teeth of this contact plate are placed insulated segments 8 with which the main line conductor 6 is connected. Movable over the double series of 45 contacts thus formed is a contact trailer carried by an insulated arm 9 driven step by step by a ratchet wheel 10 applied to its axis. This ratchet wheel is actuated by a 50 pivoted spring pressed driving pawl 11 in the end of a pivoted armature lever 12 of which 13 is the actuating magnet. The local 55 circuit of this magnet including a local battery 14 is completed through a Morse key 15 and its back stop 16. The front stop of

the Morse key is connected to a grounded transmitting battery 17 and the key is connected by conductor 18 with the insulated arm 9. 19 is a neutral relay. The two conductors or sides 5, 6 of the main line are 60 connected by a switch 20. The apparatus described is the same at both the sending and receiving stations. At one or both stations, however, the main line conductors include adjustable balancing resistances 21. The 65 magnet 13 is shown as normally on closed circuit. The arrangement might be such that it would be normally on open circuit. At the station that is to transmit, switch 20 is opened and at the receiving station it 70 is closed.

The operation is as follows: When the Morse key is depressed at station 1, the local circuit of magnet 13 is open and its armature lever 12 under the stress of its spring 75 rises, causing the pawl mounted in its end beyond its pivot to slip down over one or more ratchet teeth as may be required. When the Morse key reaches its front stop, a signal impulse is sent from battery 17 80 through the key, wire 18, arm 9 and that one of the insulated contacts 8 upon which bears the trailer of the arm into main line conductor 6. When the Morse key is lifted, magnet 13 is energized and attracts its armature causing pawl 11 to operate the ratchet wheel and carry the contact trailer onto an adjoining tooth of the toothed contact plate 7. On the next depression of the Morse 85 key, the operation is the same except that 90 the signal impulse is now sent into conductor 5 of the main line. The signal impulses pass from conductor 5 to the contact plate 7 at the receiving station, thence through the closed switch 20 to the insulated 95 contacts 8, and by trailer arm 9, wire 18 and Morse key 15 to earth through the coils of neutral relay 19. Signal impulses passing over main line conductor 6 pass to the insulated contacts 8 at the receiving station and 100 by trailer arm 9 to ground as before through the winding of neutral relay 19. It is immaterial whether normally the trailers rest upon corresponding contacts of the tables 105 of contacts. Since, however, the trailers move after each impulse, the impulses constituting component parts, either dots or dashes, of signals will pass alternately over the two conductors of the main line. The 110 conductors 5, 6, between stations may be

very widely separated and be brought into the sending and receiving stations in such way that it would be impossible for a wire tapper to have access to both of them at the 5 same time.

Fig. 2 shows the same system except that part of the main line is composed of a single conductor. Referring to Fig. 2, which shows the various parts in normal positions, 10 the apparatus at the terminal stations 1 and 4 is the same as that already described and the main line conductors 5, 6, extend to an intermediate station 2, from whence a single main line conductor 22 extends to an intermediate station 3, from whence the main line double conductors 5', 6' extend to terminal station 4. At intermediate station 2, the main line conductors 5, 6 are connected to insulated contact plates 8² and to the 15 toothed contact wheel 7², as already described. The trailer arm 9², however, is connected through the winding of a polarized relay 23² and thence through the winding of neutral relay 24 to the single main line conductor 22 extending to station 3. The main line conductors 6, 5, entering station 2 are respectively connected with the armature lever of polarized relay 23 and its 20 left hand stop. 25 The local circuit of the motor magnet 11² may be traced as follows: from the right hand contact of polarized relay 23² through the coil of the magnet, thence through the local battery 14² and armature lever of neutral relay 24 and through the back stop thereof to the armature lever of polarized relay 23². Assuming that station 1 is transmitting to station 4, switch 20 is open at station 1, and at station 4 switch 20⁴ is 30 closed. The first signal impulse sent on depression of the Morse key 15 at station 1 sends an impulse over main line conductor 6 to the insulated contacts 8² at station 2; thence through the trailer arm 9², coil of 35 polarized relay 23² and neutral relay 24 to the single main line conductor 22. The effect of this signal impulse is to place the armature lever of the polarized relay 23² against its left hand stop and to open at 40 its right hand stop the motor magnet local circuit. The next signal impulse from station 1 over the main line conductor 5 passes by the bridge connection between the conductors 5, 6, formed by the left hand stop 45 and armature lever of polarized relay 23² to the insulated contacts 8² and thence by trailer arm as before through the polarized relay 23² and neutral relay 24 to the single 50 main line conductor 22 over which, of course, 55 the dots and dashes pass in regular sequence to the neutral relay 24³ at intermediate station 3. Thence the line circuit extends through the winding of polarized re-lay 23³ to trailer arm 9³ at that station. The first 60 of such signal impulses arriving at station 65

3, sets the armature lever of polarized relay 23³ against its right hand stop and the contact trailer, being upon an insulated segment 8³, said signal impulse passes now by conductor 6' to the insulated segment 8⁴ at 70 terminal station 4. At station 3, however, the motor magnet 11³ is under control of the neutral relay 24³, the local circuit of the motor magnet being as follows: from the back stop of the neutral relay 24³ through the motor magnet winding to the right hand stop of polarized relay 23³ thence by its armature lever through the local battery to the armature lever of said neutral relay. The two main line conductors 5', 6' at station 75 3 are connected respectively with the left hand contact of the polarized relay and with the armature lever thereof, this being the equivalent of, and in effect the same as, the open switch, such as 20 at station 1. 80 When said first signal impulse passing through station 3 ceased, the armature lever of neutral relay 24³ passed to its back stop thereby closing the local circuit of motor magnet 11³. This magnet now attracts its 85 armature and moves trailer arm one step to bring the trailer onto a tooth of the toothed conductor plate 7³ so that the next signal impulse received will pass from station 3 over main line conductor 5' to terminal station 4. The receiving operation at 90 this station is the same, of course, as that already described in connection with Fig. 1. 95 When terminal station 4 is to transmit to station 1, switch 20⁴ at station 4 is opened 100 and the corresponding switch 20 at station 1 is closed. The first impulse from transmitting battery 17⁴ at station 4 places the lever of polarized armature relay 23³ at station 3 against its left hand contact, thus opening 105 the local circuit of the motor magnet 11³ and the main line conductors 5', 6' at the polarized relay armature lever and its left hand stop. At the same time, the armature lever of the polarized relay 23² at station 2 is 110 moved to its right hand contact closing the circuit of motor magnet 11² and disconnecting the main line conductors 5, 6, at the armature lever of the polarized relay 23² its 115 left hand stop. The circuit of motor magnet 11² is now under control of the neutral relay 24 and, as it is successively energized by successive impulses whether dots or dashes, the motor magnet 11² is energized and the circuit of main line conductor 22 is 120 successively transferred from the insulated contacts 8² to the contact teeth of the toothed plate 7².

On very long circuits, repeaters could be used in this system. No synchronous movement of the respective trailers is necessary and it is immaterial on what series of contacts they respectively rest.

In the system of operation herein disclosed the signal impulses are regularly 130

alternated over the two line conductors. Each conductor, therefore, carries both dot and dash signal impulses. In this detail the present system differs from that disclosed in 5 my above-mentioned patent in which all the dot signals are sent over one conductor and all the dash signals over the other conductor

I claim:

1. The combination with two main telegraph lines of a transmitter for sending dot and dash signal impulses, a transfer switch controlled by the transmitter acting to direct successive impulses alternately into the two lines and receiving means at a distant 10 station for manifesting such impulses in orderly sequence.
2. The combination with two main telegraph lines of a Morse key for transmitting dot and dash signal impulses, a transfer switch between the key and said lines controlled by the key and acting to successively 15 transfer the transmitting circuit from one line to the other and receiving means at a distant station for manifesting such impulses in orderly sequence.
- 20
- 25

3. The combination with a telegraph main line comprising a plurality of conductors of a transmitter for sending dot and dash signal impulses, an automatic transfer switch controlled by the transmitter and by which 30 the successive signal impulses are distributed to the several line conductors and receiving means at a distant station for manifesting such impulses in orderly sequence.

4. The combination with a telegraph main 35 line part of which is composed of a plurality of conductors and part of a single conductor of means for sending in orderly sequence successive signal impulses over the single conductor and distributing said impulses 40 successively in sequence to the several conductors of the other part of the line and receiving means at a distant station for manifesting such impulses in orderly sequence.

In testimony whereof, I have hereunto 45 subscribed my name.

PATRICK B. DELANY.
